RAIL-CLAMP CHOCK

Leroy Frankman, Fairmont, W. Va.

Application November 27, 1939, Serial No. 306,395

2 Claims. (Cl. 104—258)

This invention relates to a rail-clamp chock adapted for use as a stop for mine cars and the like.

The primary object of the present invention is to provide a chock of the above kind which may be effectively secured in place upon the rail and which is extremely simple and durable in construction, as well as efficient in use.

The present invention consists in the novel form, combination and arrangement of parts hereinafter more fully described, shown in the accompanying drawing and claimed.

In the drawing:

Figure 1 is a top plan view of a chock constructed in accordance with the present invention and applied to a rail.

Figure 2 is a side elevational view of the construction shown in Figure 1, partly broken away.

Figure 3 is an end elevation looking toward the left of Figure 2; and

Figure 4 is a perspective view of one of the sections of the chock shown in Figure 1.

Referring in detail to the drawing, the present chock comprises a pair of relatively thick plate-like sections 5 and 5a, preferably formed of malleable metal, and provided in their inner faces with mating horizontal grooves 6 and 6a that extend parallel with and adjacent the lower edges of the sections and are adapted for snug reception of the ball portion 7 of the rail. The chock sections are provided with transverse openings adapted to receive a bolt 8 whereby the sections are securely clamped upon the rail, and in order to facilitate alinement of the openings which receive the bolt 8 and to prevent any relative horizontal movement between the chock sections, the latter are provided on their inner surfaces with mating interfitting vertical grooves 9a and ribs 9 which are in the nature of V-shaped teeth extending from the tops of the grooves 6 and 6a to the tops of the chock sections. The opening in the section 5 for reception of bolt 8 is shown at 8a in Figure 4, and when the stem of the bolt 8 has been passed through the chock sections, a nut 10 is threaded on the projecting end of the stem of said bolt and tightened to securely clamp the chock in place. At the inner end of the chock sections, they are provided with recesses 11 which taper smaller in a forward and downward direction and are provided at the tops of the grooves 6 and 6a. These recesses 11 are adapted to receive a wedge 12 which, when driven into place between the tops of the recesses 11 and the top of the ball 7 of the rail, will serve to cause

tight engagement of the chock sections with the under side of the ball 7 of the rail so as to prevent the chock from slipping longitudinally of the rail in a direction away from the railway car whose wheel is engaged with the forward or opposite end of the chock.

As shown clearly in Figures 1 and 2, the chock section 5 is somewhat longer than the chock section 5a so that the forward end portion of said chock section 5 projects beyond the corresponding end of the section 5a for engagement with the car wheel W. Being formed of thick metallic sections, the chock will be durable, and by being fastened upon the rail in the manner described, the chock will operate efficiently for preventing retrograde movement of the car. The chock is composed of a minimum number of simple and durable parts which may be readily and cheaply manufactured, and the chock may be conveniently and quickly applied to the rail so as to effectively remain in place.

What I claim as new is:

1. A rail-clamp chock comprising a pair of plate-like sections formed in their inner faces with horizontal grooves extending adjacent and parallel to the lower edges of the sections for reception of the ball of a rail, said sections having transverse openings, a bolt passing through said transverse openings and adapted to secure the sections together upon the rail, said chock sections having forwardly and downwardly tapering recesses in the inner ends thereof and at the top of said grooves, and a wedge adapted to be driven into said recesses between the tops of the latter and the top of the ball of the rail to force the chock sections upwardly into tight engagement with the under side of the ball of the rail, said chock sections further being provided with vertical V-shaped ribs and grooves extending from the tops of said horizontal grooves to the tops of the chock sections and arranged to interfit with the transverse bolt-receiving openings of the chock sections alined.

2. A rail-clamp chock comprising a pair of plate-like sections formed in their inner faces with horizontal grooves extending adjacent and parallel to the lower edges of the sections for reception of the ball of a rail, said sections having transverse openings, a bolt passing through said transverse openings and adapted to secure the sections together upon the rail, said chock sections having forwardly and downwardly tapering recesses in the inner ends thereof and at the top of said grooves, and a wedge adapted to be driven into said recesses between the tops of

of the latter and the top of the ball of the rail to force the chock sections upwardly into tight engagement with the under side of the ball of the rail, said chock sections further being provided with vertical V-shaped ribs and grooves extending from the tops of said horizontal grooves to the tops of the chock sections and

arranged to interfit with the transverse bolt-receiving openings of the chock sections alined, one of said chock sections being longer than the other with the forward end thereof projecting for engagement with a wheel of the car to be chocked. 5

LERoy FRANKMAN.
